UNITED STATES PATENT OFFICE.

JULIUS PEGEL, OF PHILADELPHIA, PENNSYLVANIA.

DESIGN FOR A RUG.

SPECIFICATION forming part of Design No. 19,494, dated December 17, 1889.

Application filed November 23, 1889. Serial No. 331,377. Term of patent 3½ years.

To all whom it may concern:

Be it known that I, JULIUS PEGEL, a citizen of the United States, and a resident of Philadelphia, Pennsylvania, have invented a 5 Design for Rugs, of which the following is a description, reference being had to the accompanying photographic illustration, making part hereof.

A is a middle oblong square panel; B, the border. The panel is crossed diagonally by a line C of leaves and flowers, the rest of the groundwork thereof being ornamented with small detached flowers and leaves D. The space between the panel and border is covered

with large leaves intermingled and overlapping each other and at points intruding upon the inner space of the panel A, as at E, F, and G. These leaves are of various kinds and forms and varying in size.

What I claim as new is—
20 A design for rugs, as shown.
In witness that the above is my invention I have hereunto set my hand.

JULIUS PEGEL.
